(No Model.)

L. F. FOUTS.

ELECTRIC SWITCH BOARD.

No. 249,919.

Patented Nov. 22, 1881.

Fig. 2.

UNITED STATES PATENT OFFICE.

LAMBERT F. FOUTS, OF GREENFIELD, IOWA.

ELECTRIC SWITCH-BOARD.

SPECIFICATION forming part of Letters Patent No. 249,919, dated November 22, 1881.

Application filed April 8, 1881. (No model.)

To all whom it may concern:

Be it known that I, LAMBERT FREDERIC FOUTS, of Greenfield, in the county of Adair and State of Iowa, have invented a new and 5 useful Improvement in Electrical Switch-Boards; and I do hereby declare that the following is a full, clear, and exact description of the same.

The object of my invention is to provide an 10 improved switch-board for use in connection with annunciator or burglar alarms. The several doors and windows of a dwelling, hotel, or other structure, or any other desired points, are connected in a closed circuit with a battery, 15 an alarm, and my improved switch-board, the latter having a pivoted button and fixed post for each door or point in the circuit. When a "break" is made—as, for instance, when a door is opened—it may be located by moving 20 one or more of said buttons until the restoration of the circuit through branch wires connected with the aforesaid posts and the consequent arrest of the alarm give the required indications.

25 In the accompanying drawings, forming part of this specification, Figure 1 is a plan view, showing my improved switch-board, and also illustrating the connection with doors, windows, battery, and alarm. Fig. 2 is a trans- 30 verse section of the switch-board, one of the buttons being placed in the position required to complete the broken main circuit through branch wires.

The letter A indicates a base-board or bed- 35 piece, constructed of wood or other material which is a non-conducter of electricity. To the face of the board is pivoted a series of switch-buttons, B' B², &c., that are free to swing horizontally. Their free ends rest normally on metallic posts or plates C' C², &c., 40 which are isolated or otherwise insulated, and pass through the board A, as shown in Fig. 2. These posts C and the pivotal point of said switch-buttons B' are arranged in parallel lines, 45 and the number of the posts exceeds that of the buttons by one, while the number of the latter corresponds to the aggregate number of doors and windows connected in the primary circuit. The wire D completes such circuit be- 50 tween the several doors and windows and a battery, E, alarm F, and the switch-board A—

that is to say, each door and window has wires or metallic plates attached to it in such manner that when the door or window is closed such wires or plates are in mechanical contact 55 with sections of the wire D, and thus form parts or continuations of the electrical circuit, which is constantly maintained through the battery E. In this instance, as a matter of convenience, I have employed pivoted switch-plates 60 to indicate the doors and windows connected in circuit by the wire D or its several sections. The armature of the alarm F is normally held down—that is to say, it is held down so long as the circuit remains unbroken. The alarm 65 I preferably employ in such connection is the one for which I have obtained Letters Patent No. 234,765. If a door, d', or window w' be opened, the mechanical contact of the metallic connections will be broken, and hence the electrical circuit also, so that, the magnet of the alarm F being no longer charged, its armature 70 will be released, thus allowing the alarm to sound.

I connect the posts C', &c., on the rear of the 75 switch-board A and a like number of points in the primary circuit by means of a series of wires, 1 2 3 4 5. Each of these points of connection is located between two doors, d' d², or windows w' w², or between a door or window, 80 as the case may be. If, now, we suppose the switch-buttons B' B², &c., to rest on their respective posts C' C², &c., as shown in full lines, Fig. 1, and door d' to be then opened, the circuit through wire D will be broken, which fact 85 will be instantly indicated by the sounding of the alarm F. To determine which door or window of the series has been thus opened, the lever B' is moved into the notch or crevice between its post C' and the contiguous one, C², 90 thus metallically connecting such posts and re-establishing the circuit through the connecting-wires 1 and 2, which lead from posts C' C² to points respectively on the left and right of the door d'. So soon as the circuit has been 95 thus restored the battery-current again charges the magnet, and hence arrests the action of the alarm F, which fact announces that the break is at door d'. Similarly, if the door d² be opened, the alarm F will be sounded, as before, and the break may be located as follows: 100 first, turn the first switch-button, B', to the

right, as in the previous case, which will not arrest the alarm F, so that it will be apparent the door d' is not the one that has been opened. Consequently switch-button B² is next moved to the right until it locks in the crevice between posts C² C³, when the alarm will cease, since the circuit will be thus re-established through the branch or connecting wires 2 and 3 and posts C² C³. In other words, any pair 10 of the wires 1 2 3 4 5 6 may form with any two posts and a button an electrical bridge between any two points in the primary circuit.

It will be apparent that two or more breaks may be located at the same time, if required, 15 or the invention may be applied in connection with a drop-annunciator, such as is often used in hotels and telephone central offices.

What I claim as new is—

1. The combination, substantially as shown 20 and described, of a series of pivoted switch-

buttons, B', &c., corresponding in number to the doors, &c., connected in an electrical circuit therewith, a series of posts, C', &c., whose number exceeds by one that of the switch-buttons, and a series of wires for connecting such 25 posts with points in the primary circuit, as and for the purpose set forth.

2. The combination of the series of switch-buttons and the series of posts, whose number is greater by one, said posts being insulated 30 from each other, but arranged contiguously, so that when a button is moved as specified it will lock in the notch or slot between two posts, and thus be in metallic contact with both for the purpose of forming an electrical bridge, 35 as shown and described.

LAMBERT FREDERIC FOUTS.
